ABSTRACT OF THE DISCLOSURE

A method for the sterilization of surfaces utilizing essentially instantaneous and transient thermal pulses generated in a gaseous medium in contact with the surfaces by means of ignition of an explosive gas mixture or by adiabatic compression. The thermal pulses have a duration of less than about one second so that the surface is not damaged. The surface to be treated is substantially free of liquid material so that the thermal pulse acts directly upon the microorganisms.

CROSS REFERENCE TO RELATED APPLICATION

This application is a divisional of my earlier application Ser. No. 821,276, filed May 2, 1969, now U.S. Pat. No. 3,606,996.

BACKGROUND OF THE INVENTION

The present invention is concerned with methods for sterilization wherein heat in the form of transient thermal pulses generated in a gaseous medium in contact with the surface to be sterilized is utilized. More particularly the present invention utilizes thermal pulses generated in the gaseous medium for less than about one second which are produced by the ignition of a combustible composition as the gaseous medium or by the adiabatic compression and decompression of the gaseous medium.

The prior art methods of sterilization having a direct relation to the present invention particularly rely upon heating in some form for relatively long periods of time to kill microorganisms. See for instance Kirk-Othmer, volume 13 (1968) beginning at page 457 wherein various commercial sterilization methods are discussed. In general temperatures in the range of 100° to 200° C. are used for periods of time ranging from several minutes to hours. Also known is direct flame heating of the surface to be sterilized wherein the bulk of the article is heated as well to temperatures approaching the flame temperature (about 2600° C. maximum); however, this technique can produce damage to the bulk of the article and cannot be used with flammable materials. Also the use of a direct flame produces non-uniform heating of the article.

The generation of thermal pulses in a gaseous medium is known to the prior art as particularly shown by U.S. Pat. Nos. 3,175,025 and 3,329,759; however, it was not recognized that articles could be sterilized as a result of treatment and thus they were not handled so as to prevent microorganism contamination, particularly contamination by pathogenic microorganisms.

SUMMARY

It is therefore an object of the present invention to provide a method whereby sterilization can be achieved utilizing transient thermal pulses which uniformly heat the surfaces of the article. It is further an object of the present invention to provide a method wherein the article is undamaged by the thermal pulse because of the transient nature of the heating. These and other objects will become increasingly apparent from the following description.

The objects of the present invention are provided by the method for the treatment of surfaces requiring sterili-

2

zation in order to kill microorganisms on the surfaces which comprises: (a) contacting the surfaces to be sterilized with a gaseous medium, the surfaces in contact with the gaseous medium being substantially free of liquid material; (b) transiently exposing the surfaces to a thermal pulse generated in the gaseous medium having peak temperatures substantially above the minimum temperatures required to kill the microorganisms without damage to the surface; and (c) handling the surfaces so as to at least prevent pathogenic microorganism contamination before subsequent use. The use of combustible gaseous material as the gaseous medium which is ignited to produce the thermal pulse is particularly preferred.

DESCRIPTION OF DRAWING

FIGS. 1 to 3 schematically illustrate various forms of equipment which can be used in the process of the present invention. FIGS. 1 and 3 illustrate preferred forms wherein a combustible material is provided in a confined space and ignited to generate the thermal pulse. FIG. 2 illustrates a piston and cylinder arrangement for adiabatically compressing and decompressing a gaseous medium to generate the thermal pulse.

FIG. 4 schematically illustrates the steps of the method of the present invention including provision of the gaseous medium, generation of the thermal pulse and one form of handling to prevent microorganism contamination using a sealed bag.

DESCRIPTION OF THE PREFERRED EMBODIMENTS

The equipment which can be utilized in the process of the present invention is generally known to the prior art as shown by the above cited U.S. Pat. Nos. 3,175,025 and 3,329,759. The gaseous medium is provided in contact with the surface to be treated in a confined space or chamber along with a means for generating the thermal pulses in the gaseous medium, such as by the use of a combustible gaseous material and ignition or by the use of substantially adiabatic compression and decompression of the gaseous medium. The following is a brief description of preferred specific forms of such equipment.

Referring to the drawing and FIG. 1, a confined space 13 is defined by chamber 10 and cover 11 secured for instance by bolts 14. Within the confined space 13 mounted on projections 10a is provided the article 12 to be sterilized. An ignition device 15 is provided within the confined space 13 which is actuated by a spark generator means 16. A conduit and valve 18 leads into the confined space 13 which is connected to vacuum means 19 with valve 18 and provided to evacuate the confined space 13 of air. Gaseous fuel supply means 21 is provided with valve 20 to supply fuel to the confined space 13 after evacuation for ignition by the ignition means 15 and preferably and optionally a blanket gas supply means 23 with valve 22 to provide a gaseous material in the confined space 13 after ignition of the gaseous fuel to aid in the prevention of contamination after sterilization when the cover 11 is removed.

Referring to FIG. 2, a cylinder 24 is provided with a recess 25 for holding the article 27 to be sterilized and is mounted on projections 24a. A piston 26 is fitted to the cylinder 24 and a gaseous medium is provided within the defined confined space 28. The gas is compressed substantially adiabatically by applying a force F to the piston 26, thus heating the gaseous medium and the surface 27a of the article 27 for sterilization and then immediately decompressed to prevent overheating of the article.

Referring to FIG. 3, an article 30 to be sterilized is provided within a flexible bag 29, such as polyethylene bag, which is fitted with or sealed to an ignition tube 31 at the open end of the bag 29 such as by a band 32. The end of

the tube 31 outside of the bag 29 is fitted with an ignition device 34. At least the bag 29 with the article 30 can be provided in a clean chamber 33 or preferably the chamber 33 fits the confines of the bag 29 such that it is not ruptured by the ignition of the combustible gaseous material. A cover 42 with bolt 43 provides closure of the chamber 33. The ignition device 34 is provided with the spark actuator means 16 and conduit and valve 17 is attached to the exposed end of the tube 31 with the vacuum means 19 and valve 18 and gaseous fuel supply means 21 and valve 20 and operated as is the device of FIG. 1. The blanket of gaseous material after sterilization is unnecessary, since the clean chamber 33 or bag 29 is utilized and this is also possible with the devices of FIGS. 1 and 2.

Regardless of the equipment used, the method of the present invention involves three basic steps as illustrated in FIG. 4 in Steps 1, 2 and 3. In Step 1, the article 35 is provided in the confined space 37 with the gaseous medium 36 in contact with the surfaces 35a of the article 35 to be sterilized. The surfaces 35a must be substantially free from liquid material whether from the gaseous medium 36 or originally present on the article 35. If necessary the article 35 is dried to remove liquid material. The gaseous medium 36 is preferably dry. In Step 2, the gaseous medium is either compressed and decompressed or ignited to create a thermal pulse 38 having peak temperatures substantially above the minimum temperatures required to kill the microorganisms and without damage to the article 35. In Step 3, the surfaces 35a of the article 35 are handled so as to at least prevent contamination by pathogenic microorganisms before subsequent use. Preferably the article 35 is aseptically handled to prevent any microorganism contamination. Thus the article 35 can be transferred from the confined space 37 and placed in a bag 39, such as a polyethylene bag, sealed such as by a clip 40 at the open end and containing a sterile atmosphere 39. Where the device shown in FIG. 3 is utilized such that the chamber 33 prevents rupture of the bag 29 during ignition of the combustible gaseous materials by confining the bag 29, this has been found to be a simple and inexpensive means of preventing contamination before used and is preferred. The ignition products of the combustible gaseous material are sterile and thus do not need to be replaced with a blanket gaseous material although it is preferred to use the blanket gaseous material in instances where the ignition products could be damaging to the article in order to prevent chemical contamination of or reaction with the articles treated.

The article to be sterilized must be bathed by the thermal pulse on all surfaces to be sterilized. This is accomplished by mounting the article on support means in the confined space which allow the gaseous medium to contact the surfaces to be treated, such as the optional projections 10a, 24a and 33a shown in FIGS. 1 to 3 which provide minimum contact with the surfaces to be sterilized. Alternatively the article can be repetitively treated with repositioning of the surfaces of the article to insure treatment with the thermal pulse.

The gaseous medium utilized will depend upon the equipment used and the composition of the article being sterilized. Where adiabatic compression equipment is used it is preferred to use a gaseous medium which is compatible with the article being treated. Thus rare gases or hydrogen or nitrogen have been used with good result. Where the composition of the article is resistant to destructive oxidation, such as stainless steel, oxygen can be used which further augments the treatment with the thermal pulse because of oxidative destruction of the microorganisms.

Where ignition of a combustible gaseous material is used, it is preferred to use a mixture of an oxidizable gaseous material and an oxidizer gaseous material which is compatible with the material being treated such that the by-products of combustion do not contaminate or react with the article or otherwise adversely affect the article.

For this reason methane (or other lower alkanes, alkenes and alkynes containing 1 to 4 carbon atoms) and hydrogen are the preferred oxidizable materials and air or oxygen are the preferred oxidizer materials since water and/or carbon dioxide is generated by the reaction. Oxidizing conditions, as discussed above, can be produced by providing a stoichiometric excess of the oxidizer, oxygen. Other oxidizable materials which can be used are for instance ammonia, hydrazine, hydrogen sulfide, carbon monooxide and various hydrocarbons such as acetylene, ethylene oxide and cyanogen. Suitable oxidizer materials are pure oxygen which is preferred, oxygen with gaseous diluents such as air, air alone, halogens such as fluorine and chlorine, ozone and various nitrogen oxide. Mixtures of single or multiple oxidizer materials with single or multiple oxidizable materials can be used, but these are not preferred because of the possible effect on the article of the by-products of the reaction. The energy produced by the combustible gaseous material can be increased or decreased by regulating the charge pressure prior to ignition. Various compounds which rapidly decompose with accompanying transient release of thermal energy upon suitable initiation can also be used singly or multiple to produce the transient elevated gaseous temperatures such as acetylene and nitrogen dioxide.

In each instance the thermal pulse generated is transient, and usually this step is complete in less than one second. The treatment does not damage or destroy the article because the surfaces in contact with the gaseous medium are only briefly in contact with the thermal pulse while the bulk of the article is only heated to a limited degree. Also, the total energy of the thermal pulse is maintained at less than the energy which would damage or destroy the article. For this reason articles composed of metals, ceramics, plastics and naturally occurring materials can be sterilized. Woven and non-woven fabrics, such as blankets and bandages and the like, stainless steel medical instruments and other articles with surfaces requiring sterilization have been successfully treated.

Having generally described the method of the present invention, the following are specific examples.

Example 1

Utilizing the equipment illustrated in FIG. 1, a roll of square woven fabric (cotton and polyester fiber) six inches (6") long and four inches (4") in diameter was provided in the chamber 10 measuring four and one half inches (4½") in diameter by six and one-quarter inches (6¼") high. The chamber 10 was closed with the cover 11 and bolted with bolts 14. The chamber was evacuated to 10 mm. of Hg and then a combustible mixture of sixty percent (60%) hydrogen and forty percent (40%) oxygen by volume (molar excess of oxygen) at three atmospheres absolute was provided in the confined space and ignited. A blanket of nitrogen was then provided in the confined space and then the cover was removed and the article transferred to a sterile bag for subsequent use. It was found upon culture testing of a portion of the article that it was sterile and that the article was undamaged by the treatment.

Example 2

The treatment of Example 1 was repeated with the same size roll of cotton muslin using a mixture of sixty-six and two-thirds percent (66⅔%) hydrogen and thirty-three and one-third percent (33⅓%) oxygen by volume (stoichiometric mixture) at two atmospheres absolute. The results were the same as those of Example 1.

Example 3

The treatment of Example 1 was repeated with a polypropylene perforated tube measuring six inches (6") long by one and three-eighths inches (1⅜") in diameter used as a support for microfiltration using a mixture of seventy-five percent (75%) hydrogen and twenty-five (25%)

oxygen by volume at four atmospheres absolute. The results were the same as those of Example 1.

Example 4

The procedure of Example 1 was repeated using a two inch (2") diameter by two and one-half inches (2½") high chamber with a stainless steel (300 series) surgical pin measuring two inches (2") long by one-half inch (½") in diameter using a mixture of fifty-two percent (52%) hydrogen and forty-eight percent (48%) oxygen (stoichiometric excess of oxygen) by volume at 500 p.s.i.g. The results were equivalent to those of Example 1.

Example 5

The procedure of Example 4 was repeated with a gold alloy dental crown using a mixture of seventy-five percent (75%) hydrogen and twenty-five percent (25%) oxygen by volume (stoichiometric excess of hydrogen) at 500 p.s.i.g. The results were equivalent to those of Example 1.

Example 6

The procedure of Example 1 was repeated with a non-woven fabric of three (3) denier polypropylene fiber measuring six inches (6") long by four inches (4") in diameter using a mixture of sixty-six and two-thirds percent (66⅔%) hydrogen and thirty-three and one-third percent (33⅓%) oxygen by volume (stoichiometric) at two atmospheres absolute. The results were equivalent to those of Example 1.

Example 7

Using the equipment illustrated in FIG. 2, wherein the confined space 28 measured eighteen inches (18") long and two inches (2") in diameter, portions of the articles of Examples 1 to 6 were provided in the recess 25 in an atmosphere of nitrogen as a neutral atmosphere, hydrogen as a reducing atmosphere or in certain instances oxygen as an oxidizing atmosphere and the gas rapidly compressed and decompressed along the eighteen inch length of the chamber by the piston 26 such that there was a gas compression ratio of about 40 to 1. The results were similar to those of Examples 1 to 6.

Example 8

Using the equipment of FIG. 3, a large steel enclosure was provided measuring three feet (3') in diameter by six feet (6') long. A large roll of cotton gauze was provided in a polyethylene bag 29 and the enclosure 33 filled with the bag and roll. The treatment of Example 2 was repeated with equivalent results.

Example 9

To test the effectiveness of sterilization a polyethylene film surface was smeared with the pathogenic bacteria *Escherichia coli* and subjected to the treatment of Example 2. It was found the *E. coli* was killed.

Example 10

To test the effectiveness of sterilization, the bacteria *Bacillus stearothermophilus* was smeared on a steel surface and subjected to the treatment of Example 4. This bacteria is utilized by those skilled in the sterilization art to determine the efficacy of sterilization and normally requires steam at 250° F. for 15 minutes to kill it. Culturing at above about 55° C. is required for growth. It was found that the bacteria was killed.

In the manner of Examples 1 to 10, microorganisms including virus, bacteria, mold and yeast were treated by the method of the present invention and killed. It was found that the thermal pulse preferentially heated the 70

microorganisms on the surfaces to the destruction point because of their very small size and thin cross-section so long as there was no masking effect by liquids or solids on the surfaces to be sterilized.

5 In the handling of the article after sterilization, any one of various known techniques can be utilized. The article can be kept in the sterilizing unit before use or be placed in a sterile container. In any event, care must be taken to prevent contamination by at least pathogenic microorganisms before use and possible even during use for some applications.

10 It is intended that the foregoing description be only illustrative of the present invention and it is intended that the present invention be limited only by the hereinafter appended claims.

15 I claim:

1. The method for the treatment of surfaces requiring sterilization in order to destroy microorganisms on the surfaces which comprises:

20 (a) contacting the surfaces to be sterilized with a gaseous medium in a sealed and confined space defined by a rigid chamber, the surfaces in contact with the gaseous medium being substantially free of liquid material which masks the surfaces from sterilization;

25 (b) transiently exposing the surfaces to a thermal pulse generated by the substantially adiabatic compression of the gaseous medium confined by the rigid chamber to produce peak temperatures substantially above the minimum temperatures required to destroy the microorganisms without damage to the surfaces and then decompressing the gaseous medium to prevent damage to the surfaces; and

30 (c) moving the surfaces from the chamber and confining the surface in a sealed bag so as to at least prevent pathogenic microorganism contamination before subsequent use while maintaining sterile conditions.

35 2. The method of claim 1 wherein oxidizing conditions are maintained in the gaseous medium during generation of the thermal pulse.

40 3. The method of claim 1 wherein the surface to be treated is dried to remove liquid material before being contacted with the gaseous medium and wherein the gaseous medium is substantially dry.

45 4. The method of claim 1 wherein the surface is aseptically handled prior to use to prevent microorganism contamination.
